UNITED STATES PATENT OFFICE.

PAUL F. WEISS, OF CHICAGO, ILLINOIS, ASSIGNOR OF ONE-HALF TO HAROLD J. PETERSON, OF CHICAGO, ILLINOIS.

ELECTRIC HEATING APPARATUS.

Application filed April 30, 1926. Serial No. 105,773.

The present invention relates to electric heating apparatus and has particular reference to that type of heating apparatus wherein the heat is generated within a body 5 of liquid by passing the electric current therethrough.

One of the principal objects of the invention is to provide an improved construction of radiator for household heating employing this general principle of operation. The advantages of this method of heating a building, room or other premises are manifest. For example, this method of heating dispenses entirely with boilers, furnaces, 15 fuels, piping and all of the objections incident thereto. One of these heating radiators can be placed in each room or other area to be heated and the current necessary for the operation of these heaters can be derived 20 from the ordinary electric lighting circuit, or from a separate power circuit having lower rates for large electrical consumption.

While the advantages of household heating by electricity have long been recognized, 25 apparatus heretofore available for this purpose has been subject to numerous objections.

One of the principal objections to this type of apparatus, as heretofore constructed, has been the comparatively short life of 30 the resistance element in which the electrical energy is converted into heat. Furthermore, such resistance elements have a very small area of heat radiating surface and 35 consequently have to operate with a very intense heat concentrated in the immediate proximity of the heating resistance with the result that such devices are likely to burn objects placed near them. Obviously, with 40 all of the heat required for heating a room emanating from a localized point there is no uniformity of distribution of the heat with this type of heating apparatus. They are also subject to the objection that they have 45 no reserve capacity for storing up heat for later dissipation into the room after the current has been turned off. I have avoided all 50 of these objections in the present radiator construction by first converting the electrical energy into heat within a liquid which is contained in the radiator and which serves as the resistance medium; and then dissipating the heat thus generated by radiation

from the relative large surface area of the radiator. 55

One of the more specific objects of the invention is to provide an improved manner of regulating the temperatures in a radiator of this type. This temperature regulation is preferably effected by varying the resistance of the electrical path through the liquid, such as by varying the depth of immersion of a movable electrode to vary the spacing between two electrodes or by varying the area of contact between the liquid and one of these electrodes. This feature of my invention has application to all types of heating apparatus utilizing a liquid as the resistance medium. For example, the invention may be utilized for heating glue 60 pots and other similar devices where a uniform, closely regulated temperature is desired. 65

Another object of the invention is to provide a construction of radiator of like heating device of this general nature in which the outer shell or casing is insulated from both sides of the circuit so that there is no possibility of its becoming "grounded" or causing a shock when touched. 70

Other objects and advantages inherent in my invention will appear from the following description of a preferred embodiment thereof. 75

In the drawing illustrating this embodiment:

Figure 1 is a vertical sectional view through a radiator, such as might be employed for household heating; and

Fig. 2 is a similar view through a modified construction.

Referring first to the adaptation shown in Fig. 1, the radiator comprises any desired form of outer casing 8 constructed either as a casting or of sheet metal, and having any 95 suitable supporting feet 9. In the construction shown, the radiator is made of sheet metal, the side and bottom walls 11 and 12 thereof being formed from a single sheet or separately, as desired. The top of this 100 casing is closed by a top plate 14 which is bolted or otherwise secured to the marginal flange 15 extending from the upper edges of the side walls 11.

Supported in the lower part of this main 105 or outer casing is a chamber or pan 17 which

contains the conducting liquid 18 and which is insulated from the outer casing. The corners and bottom of this inner container may be insulated from the outer casing by the interposition of insulating spacers 19 and 21 between the two. The upper edge of this inner container is joined to the side walls of the outer casing by any suitable construction of insulating seal. For example, a stotted bead 22 of insulating material may be pressed down over the upper edge of this inner container, with the outer side of this insulating bead bearing firmly against the side walls of the outer casing. A sealing flange 23 is riveted or otherwise secured to the side walls of the outer casing for pressing down over the top and inner side of this insulating bead. This sealing flange is also formed with an inwardly flaring drip edge 25 which prevents any condensation seeping down over the sealing flange from bridging the insulating bead 22 and thereby tending to ground the outer casing. As will hereinafter appear, this inner container is connected to one side of the electrical circuit and constitutes the stationary electrode for passing the electrical current through its contained liquid 18. By thus insulating this inner container from the outer casing in the manner hereinbefore described, the chance of grounding that might occur would be through a path of such high resistance that it would be of no consequence.

The liquid in the inner container is maintained at a substantially definite level, at approximately the point indicated, and dipping into this liquid is a movable electrode 28 tiltably suspended, preferably at one end thereof, from a stationary bracket 40 or hanger 29 which is secured to the top plate 14 of the outer casing. This bracket or hanger is insulated from the movable electrode in any suitable manner, as by interposing a relatively long insulator 31 in the length of the hanger. The lower end of the insulator or hanger is hinged or pivoted to the movable electrode; for example by a Z-shaped sheet metal strap 32 which will have ample flexure to permit the limited tilting movement of the electrode.

The movable electrode extends through a considerable part of the length of the inner container, and is so arranged with respect thereto that the shortest path of conductivity between the movable electrode and the inner container or stationary electrode 17 is in a direction downwardly through the liquid to the bottom wall of the container or electrode 17, whereby the major portion of the current flow will be through this path of least resistance. Hence, it will be seen that by raising and lowering the movable electrode 28 the spacing between different portions of the two electrodes will vary in this path and the resistance will be increased

or diminished. At any preferred point, preferably intermediate its ends, this movable electrode has operative connection with a control rod 34. The electrode is insulated from the control rod by the interposition of an insulator 35 between the two. The lower end of the insulator is secured to the movable electrode by a thin sheet metal strap section 36, similar to the strap section 32. The control rod 34 has a swiveled connection 37 with the upper end of the insulator, whereby the control rod can be rotated relatively to the insulator.

The control rod has operative connection at its upper end with a pressure responsive element 38. This pressure responsive element may consist of a diaphragm, a bellows, or a sylphon, one side of which is subjected to the pressure within the casing and the other side of which is acted on by atmospheric pressure. In the preferred construction shown, this pressure responsive element is of that type commonly known as a sylphon, the latter having its lower end open so that the interior thereof will be subjected to the pressures generated within the casing. This open lower end is soldered or otherwise secured to a flange 39 extending inwardly from a cylindrical supporting shell 41, depending from the cover plate 14. This supporting shell has a hinged cover 42 having holes 43 therein, through which atmosphere is admitted into the annular space in the shell 41 surrounding the sylphon 38. The control rod 34 has its upper end threaded and this threaded end screws up through a threaded boss 44 formed in the top plate 45 which closes the top of the sylphon 38. The upper end of this control rod is provided with a knob 46 by which the rod can be screwed up and down in the boss 44 to adjust the height of the movable electrode relative to the upper end of the sylphon, or relative to the level of the liquid 18.

A compression spring 47 bears at its lower end against the end plate 45 of the sylphon. The upper end of this spring bears against a ring 48 which screws into an internal thread formed in the upper end of the shell 41. This ring is formed with a flange or any other form of gripping means by which it can be grasped for screwing the ring up or down in the shell and thereby varying the pressure of the spring 47.

It will be seen that the above construction provides two adjustments, one for varying the effective length of the control rod 34 and the other for adjusting the normal spring pressure impressed on the upper end of the sylphon. Both of these adjustments are readily accessible by raising the hinged cover 42. By adjusting the effective length of the control rod 34, the area of the movable electrode in contact with the liquid 18 can be adjusted for any given pressure and tem-

perature. By adjusting the pressure of the spring 47, the maximum pressure and temperature which the radiator will normally tend to maintain can be adjusted to any desired point.

The shell 41 is dropped through an opening in the cover plate 14 and has a flange 51 which is bolted to the cover plate around this opening. The electrical connections are established through a socket 52 which is secured to this flange 51 and which has a long insulating portion 52' extending down through an opening 53 in the cover plate 14. The two conductors 54 and 55 extend down from this insulating portion 52' and establish connection with the inner container 17 and with the movable electrode 28, the flexibility of the conductor 55 permitting the controlling movement of the movable electrode. Insulating sheathing 56 is provided on the upper portions of these conductors. Electrical connection may be made with the light circuit or with a power circuit through the outer conducting lead 57 and a conventional terminal plug 58 receivable in the socket 52.

A vent plug 59 is provided to close a vent in the top plate of the outer casing. The inner container may receive its charge of conducting liquid through this vent opening or through a filling inlet 61 entering the lower part of the outer casing. Where such filling inlet is employed, it is located substantially coincident with the desired liquid level in the inner container so that in charging the radiator the liquid can only be brought up to this level. This inlet consists of an elbow section having its inner end joined to the container 17 and its outer end extended upwardly and threaded for receiving a closure plug 62. An insulating bushing 63 insulates this filling inlet from the outer casing where it passes through the casing.

A drain cock 65 may also be provided for draining the inner container 17. The upper end of this drain cock is joined to the container and the cock extends through an insulating bushing 66 in passing down through the outer casing.

In the operation of the device the effective length of the control rod 34 and the pressure of the spring 47 are preferably so adjusted that with the radiator cold the movable electrode will be immersed to a sufficient depth to insure a relatively large current flow when the device is started into operation so that the liquid will heat up quickly. As the liquid rises in temperature, the confined volume of air or gas in the upper part of the radiator will absorb some of the heat and expand, thereby acting on the sylphon to raise the movable electrode slightly and reduce the current flow. As soon as the liquid begins to boil the steam

or other vapor will commence building up a pressure in the upper part of the container, which pressure is employed as the regulating factor for controlling the working temperature of the radiator. By constructing the electrode 28 with a relatively extensive area, as shown, a nicely graduated controlling action can be obtained, the sylphon holding the movable electrode in a position corresponding to a current flow commensurate with the desired temperature at which the radiator is to be maintained. In constructing the movable electrode 28 to have a relatively large surface area for contact with the liquid 18, two or more spaced plates 67 and 68 may be joined together by bolts or rivets 69 passing through spacing sleeves which hold the plates in spaced relation.

The modification illustrated in Fig. 2 differs principally from the preceding embodiment in the particular form of the casing and in the form of the movable electrode. In this embodiment the casing 70 is constructed of two concentric cylindrical shells 71 and 72 which define a chamber annular in form at the lower part of the casing. The top of this chamber is closed by a circular cover plate 73 and the bottom is closed by an annular plate 74 joined to the lower edges of both shells 71 and 72. A flanged plate 75 closes the upper end of the inner shell 72. The movable electrode 28' comprises a series of spaced annular plates or rings 76 adapted to have a variable contact with the liquid 18, similarly to the movable electrode 28. These annular plates or rings are supported on rods 77, depending from the ends of a multiple arm spider 78. The annular electrode members 76 are supported in spaced relation on the rods 77 by interposed washers 79.

The spider 78 is suspended through an insulator 35' from a control sylphon which is disposed centrally of the casing. This control sylphon is a substantial duplicate of the sylphon just described, and accordingly I have not illustrated the same in detail. It will have a similar adjustable spring 47 and adjustable connection between the control rod 34 and the upper end of the sylphon, for affording the two adjustments previously described. The electrical connections to the movable electrode and to the main casing 70 will be evident from the preceding description.

In many instances there will be no objection to the outer casing of the device being "live" or "grounded". However, where this is objectionable, the casing 70 may be completely enclosed by an outer perforated cage or screen 81 which is insulated from the main casing. The top of such cage or screen may be insulated from the main casing by an insulating ring 82 which engages down over the joining flanges 71' and 73' of the casing.

The lower edge of this screen is insulated from the casing by insulating blocks 83 secured between the two. This screen has a multiplicity of apertures or slots 84 therein through which air can circulate for contact with the main casing. This screen can be readily removed for affording access to the control adjustments. It will be noted that the lower annular wall 72 increases the heat radiating surface of the casing.

In each of the preceding constructions the movable electrode, together with the metallic wall which constitutes the stationary electrode, will both be constructed of a metal or metals between which there will be no "plating" action. For the conducting liquid ordinary water will suffice, although I also contemplate the use of certain other conducting liquids, which in their electrolysis, will not liberate any obnoxious or dangerous gases. This electrolysis will be so slight, particularly when using alternating current, that it may be disregarded. Moreover, in both embodiments, the main casing is hermetically sealed so that any gas created in the casing cannot escape, until the vent is opened.

What I claim as my invention and desire to secure by Letters Patent of the United States, is:

1. In an electrically operated radiator, the combination of a container comprising a stationary electrode portion, said container being adapted to contain a conducting liquid therein, a movable electrode adapted to have a portion thereof immersed in said liquid for establishing a conducting path through said liquid between said electrodes, and control means operating upon said movable electrode for controlling the temperature of said radiator.

2. In electrically operated heating apparatus, the combination of a container comprising a stationary electrode portion, said container being adapted to contain a conducting liquid therein, a movable electrode adapted to have a portion thereof immersed in said liquid for establishing a conducting path through said liquid between said electrodes, and control means for varying the depth of immersion of said movable electrode in said liquid.

3. In electrically operated heating apparatus, the combination of a container comprising a stationary electrode portion, said container being adapted to contain a conducting liquid therein, a movable electrode adapted to have a portion thereof immersed in said liquid for establishing a conducting path through said liquid between said electrodes, and control means for varying the area of contact between said movable electrode and said liquid.

4. In electrically operated heating apparatus, the combination of a container com-

prising a stationary electrode portion, said container being adapted to contain a conducting liquid therein, a movable electrode adapted to have a portion thereof immersed in said liquid for establishing a conducting path through said liquid between said electrode, and pressure responsive means operating to control said heating apparatus by changing the position of said movable electrode relative to said liquid.

5. In electrically operated heating apparatus, the combination of a container comprising a stationary electrode portion, said container being adapted to contain a conducting liquid therein, a movable electrode adapted to have a portion thereof immersed in said liquid for establishing a conducting path through said liquid between said electrodes, and a pressure responsive element for raising and lowering said movable electrode relative to the liquid level in said container.

6. In electrically operated heating apparatus, the combination of a container comprising a stationary electrode portion, said container being adapted to contain a conducting liquid therein, a movable electrode adapted to have a portion thereof immersed in said liquid for establishing a conducting path through said liquid between said electrodes, pressure responsive means for moving said movable electrode in said liquid to vary the current flow through said liquid, and means for adjusting the responsiveness of said pressure responsive element to different pressures.

7. In electrically operated heating apparatus, the combination of a container comprising a stationary electrode portion, said container being adapted to contain a conducting liquid therein, a movable electrode adapted to have a portion thereof immersed in said liquid for establishing a conducting path through said liquid between said electrodes, a pressure responsive element, an operating connection between said movable electrode and said pressure responsive element, and means for varying the effective length of said operating connection.

8. In electrically operated heating apparatus, the combination of a container comprising a stationary electrode portion, said container being adapted to contain a conducting liquid therein, a movable electrode adapted to have a portion thereof immersed in said liquid for establishing a conducting path through said liquid between said electrodes, a pressure responsive element subjected to the pressures generated within said container, an operating connection between said pressure responsive element and said movable electrode, and means for adjusting the immersion of said movable electrode in said liquid for a predetermined condition of said pressure responsive means.

9. In electrically operated heating appa-

ratus, the combination of a container comprising a stationary electrode portion, said container being adapted to contain a conducting liquid therein, a movable electrode 5 adapted to have a portion thereof immersed in said liquid for establishing a conducting path through said liquid between said electrodes, and means for insulating said electrodes and the conducting liquid from the 10 outer surface of the device.

10. In an electrically operated radiator, the combination of a casing comprising a stationary electrode portion, said casing being adapted to contain a conducting liquid, 15 a movable electrode partially immersed in said liquid, a supporting bracket extending between said casing and said movable electrode for tiltably supporting said electrode, a sylphon supported by said casing with one 20 side subjected to atmosphere and the other side subjected to the pressures generated within said casing, an operating member connecting said movable electrode with said sylphon, a spring resisting flexure of said 25 sylphon under the pressures generated within said casing, and means for adjusting the position of said movable electrode relative to a predetermined pressure within said casing.

30. 11. In an electrically operated radiator, the combination of a casing comprising a stationary electrode portion, said casing being adapted to contain a conducting liquid, a movable electrode adapted to have a portion 35 thereof immersed in said liquid for establishing a conducting path therethrough between said electrodes, a sylphon mounted in said casing having one side subjected to the pressures generated within said casing, 40 a motion transmitting connection between said sylphon and said movable electrode, a

spring reacting against said sylphon, means for adjusting said motion transmitting connection, and means for adjusting said spring.

45

12. In electrically operated heating apparatus, the combination of a main casing, an inner container insulated from said main casing and adapted to contain a conducting liquid, and electrode means having contact 50 with said liquid for establishing a current flow through said liquid.

13. In electrically operated heating apparatus, the combination of a main casing, an inner container insulated from said main 55 casing and adapted to contain a conducting liquid, said inner container constituting one electrode, and a second electrode having a portion thereof immersed in said liquid for establishing a conducting path therethrough. 60

14. In electrically operated heating apparatus, the combination of a casing comprising a stationary electrode portion, said casing being adapted to contain a conducting liquid, a second electrode adapted to have a portion 65 thereof immersed in said liquid for establishing a conducting path through said liquid, and a screen over said casing and insulated therefrom.

15. In an electrically operated household 70 heater, the combination of a casing, an inner container electrically insulated from said casing and adapted to contain a conducting liquid, electrode means having contact with said liquid for establishing a current flow 75 through the liquid, and automatic control means for regulating the working temperatures of said heater by effecting movement of said electrode means within said container.

PAUL F. WEISS.
